UNITED STATES PATENT AND TRADEMARK OFFICE
CERTIFICATE OF CORRECTION

PATENT NO. : Des. 490,413 S
DATED : May 25, 2004
INVENTOR(S) : Thomas Arbisi

Page 1 of 1

It is certified that error appears in the above-identified patent and that said Letters Patent is hereby corrected as shown below:

Title page,
Item [57], **CLAIM**,
DESCRIPTION, the following sentence has been inserted:

-- The broken line showing of the internal surfaces and the extending tabs is for illustrative purposes only and forms no part of the claimed design. --

Signed and Sealed this

Fourteenth Day of December, 2004

A handwritten signature in black ink, appearing to read "Jon W. Dudas". The signature is written in a cursive style with a large, stylized "J" and "W".
